(57) **CLAIM**

The ornamental design for a gaming machine deck as shown and described herein.

DESCRIPTION

FIG. 1 is a front top perspective view of a gaming machine deck of our new design.

FIG. 2 is a front view of the gaming machine deck of FIG. 1.

FIG. 3 is a rear view of the gaming machine deck of FIG. 1.

FIG. 4 is a right side view of the gaming machine deck of FIG. 1.

FIG. 5 is a left side view of the gaming machine deck of FIG. 1.

FIG. 6 is a top view of the gaming machine deck of FIG. 1.

FIG. 7 is a bottom view of the gaming machine deck of FIG. 1.

FIG. 8 is a front top perspective view of a gaming machine deck of another embodiment of our new design.

FIG. 9 is a front view of the gaming machine deck of FIG. 8.

FIG. 10 is a rear view of the gaming machine deck of FIG. 8.

FIG. 11 is a right side view of the gaming machine deck of FIG. 8.

FIG. 12 is a left side view of the gaming machine deck of FIG. 8.

FIG. 13 is a top view of the gaming machine deck of FIG. 8.

FIG. 14 is a bottom view of the gaming machine deck of FIG. 8.

FIG. 15 is a front top perspective view of a gaming machine deck of another embodiment of our new design.

FIG. 16 is a front view of the gaming machine deck of FIG. 15.

FIG. 17 is a rear view of the gaming machine deck of FIG. 15.

FIG. 18 is a right side view of the gaming machine deck of FIG. 15.

FIG. 19 is a left side view of the gaming machine deck of FIG. 15.

FIG. 20 is a top view of the gaming machine deck of FIG. 15; and,

(Continued)

FIG. 21 is a bottom view of the gaming machine deck of FIG. 15.
 The portions shown in phantom are not part of the claimed design.

1 Claim, 6 Drawing Sheets
